UNITED STATES PATENT OFFICE.

WALTER PETTIT, OF CLARE, MICHIGAN.

DISPLAY DEVICE.

Application filed July 23, 1926. Serial No. 124,456.

This invention relates to display devices, and particularly to a device for raising water in the old fashioned way, and which may also serve for the practical operation 5 of raising water from a well, or it may be connected to an underground main if desired.

One object of the invention is to design a practical and unique display and advertising device which can be set up in show windows for advertising certain products or articles.

Another object is to design a practical display device and provide a rotating member containing advertising matter which can be changed or varied as desired.

A further object is to provide a display device provided with a bucket, and provide means for intermittently raising and 20 dropping the said bucket.

With the above and other objects in view, the present invention consists in the combination and arrangement of parts, herein-after more fully described, illustrated in the 25 accompanying drawing, and particularly pointed out in the appended claims, it being understood that changes may be made in the form, size, proportion and minor details of construction without departing from 30 the spirit or sacrificing any of the advantages of the invention.

In the drawing:

Fig. 1 is a vertical part sectional view of my improved display device showing the 35 bucket in raised position.

Fig. 2 is a side view thereof showing a manikin grasping the handle of the crank.

Fig. 3 is an enlarged sectional detail of the advertising attachment.

Fig. 4 is an end view thereof.

Fig. 5 is an enlarged detail showing the drive chain.

Fig. 6 is a transverse sectional view through one of the advertising boxes.

Referring now particularly to the drawing, the numeral 5 indicates the platform of the structure to which a housing 6 is secured, and which is substantially similar to the curb of an old fashioned well, hollow

post members 7 project upwardly from this 50 housing and a roof 8 is supported thereon in the usual manner.

A centrally disposed leak proof opening 9 is provided in the housing 6 and can be formed of wood, sheet metal or cement as 55 desired, a tubular casing 10 being sunk in the ground below the housing, and a water pipe 11 is connected thereto and supplies water for said device, or it can be set over a conventional well if desired.

A motor 12 is mounted in the housing 6 as shown, and power can be supplied from any convenient source, a shaft 13 being journaled in suitable bearings 14 which are secured to the said shaft and is geared to the 65 motor by means of the belt 16 which is trained over a drive gear 17 fixed on the motor shaft.

As above noted these uprights 7 are hollow, and a shaft 18 is journaled in suitable 70 bearings 19 secured thereto, a sleeve 20 being rotatably mounted on said shaft, and a drum 21 is secured on one end of the sleeve, a sprocket 22 being fixed on the opposite end within the upright. A crank 23 75 is secured on the one end of the shaft 18, and sprockets 24 and 25 respectively, are mounted on this shaft within the hollow upright, a similar sprocket 26 being mounted on the shaft 13 and is geared to the 80 sprocket 24 by means of a chain 27, said chain being provided at spaced apart intervals with laterally projecting spaced apart pins 28 adapted as the mechanism is driven, to engage the teeth on the sprocket 25 for 85 winding the drum 21 and raising the bucket 29 which is attached thereto by means of a rope or cable 30 the bucket then falls back into the well and the operation is repeated.

An advertising apparatus 31 is mounted 90 directly above the drum 21, and comprises a pair of spaced apart end members 32 connected by means of a plurality of hollow shaft members 33, the end members being provided with stub shafts 34 secured thereto, and journaled in suitable bearings 35 secured to the posts 7.

Individual display boxes 36 are pivotally

- mounted on each of the hollow shafts 33 and comprise top and bottom members 37 suitably rabbeted to receive the glass plates 38, the members 37 being covered by a metal cap 39, the edges of which are turned as shown at 39^a in Fig. 5. of the drawing, so that suitable strips containing indicia thereon may be inserted endwise, or by flexing the strip, or suitable glass plates may be inserted endwise.
- 10 A sprocket 40 is mounted on the stub shaft 34 in the position as shown, and a short section of hollow shaft or sleeve 41 is mounted in a suitable bearing 42 secured to the wall of the post 7, the opposite end receiving the 15 end of the shaft 34 and forming a bearing, another sprocket 43 is mounted on the shaft 41, and is geared to the sprocket 22 by means of the chain 44, which chain is provided with suitable spaced apart pins 28 identically 20 similar to those on the chain 27, these pins engaging the sprocket 40 at certain intervals for rotation of the display apparatus, the timing, etc., being governed by the spacing of the pins 28 on the chain.
- 25 Due to the spacing of the hollow shafts 33, and depth of structure 31, it will be obvious that as the device is rotated, that the display boxes 36 will always hang in a vertical readable position.
- 30 A plunger 45 is mounted on a rod 46 within the casing 10, and is pivotally connected to the bottom of the bucket in any approved manner, this bucket drops by gravity when the pin disengages from the drive sprocket, 35 and is raised by rotation of the drum caused by the pins 28 engaging the sprocket 25, this raising and dropping of the bucket setting up a pumping action for supplying water if desired, and in practise I provide a jointed 40 manikin who grasps the crank 23, whereas in reality, the manikin is operated by the motor, I also make the manikin's head detachable so that another may be mounted thereto and to represent different nationality.
- 45 From the foregoing description, it will be obvious that I have perfected a very attractive, interesting and practical display and advertising device.

What I claim is:—

- 50 1. In a machine of the character described, the combination with a housing having a source of water supply, of a pair of hollow supports, a transversely disposed shaft and sleeve, a drum mounted thereon and a bucket hung therefrom, a crank, a jointed manikin connected thereto, means for driving said shaft and means for intermittently driving said sleeve.
- 55 2. A display device comprising a platform, a housing, upright posts mounted on the housing and a roof thereon, a shaft journaled in said uprights, a sprocket mounted thereon, a sleeve on the shaft, a sprocket mounted thereon, a drum on the sleeve and a bucket hung therefrom, a power

plant, a chain for driving said sprocket and means on the chain for intermittently rotating the sleeve.

3. A display device comprising a housing, a power plant housed therein, hollow uprights mounted on said housing, a shaft journaled in said uprights, a sprocket mounted thereon, a sleeve on the shaft, a drum on one end of the sleeve, a bucket hung therefrom, and a sprocket on the other end of the sleeve, a chain connecting said shaft and power plant, and means on the chain for intermittently engaging and driving the sprocket on the sleeve.

4. A display device comprising a housing having a roof supported by spaced apart hollow posts, a shaft journaled in said posts, a sprocket mounted thereon, a sleeve on the shaft, and a drum on one end of the sleeve, a bucket flexibly hung therefrom, a sprocket on the opposite end of the sleeve, a motor in the housing, a chain connecting said power plant and shaft and laterally extending pins on the chain for engaging the sprocket on the sleeve to rotate the sleeve.

5. A display device comprising a housing, a roof mounted thereon, and supported by spaced apart hollow posts, a shaft journaled in said posts, a sprocket mounted thereon, and a crank on one end to which a jointed manikin is connected, a sleeve on the shaft, a drum mounted on one end of the sleeve, and a sprocket on the opposite end of the sleeve, a power plant in the housing, a chain connecting said power plant and shaft, and laterally projecting pins on the chain and adapted to engage the sprocket on the sleeve for winding said drum.

6. In combination with a machine of the character described, a housing having a pair of hollow posts, a transversely disposed shaft journaled in said posts, a sleeve thereon, a drum on the sleeve and a bucket connected thereto, sprockets on the shaft and sleeve respectively, a power plant, a chain connecting the power plant and shaft, a display mechanism comprising a frame, individual display boxes pivotally mounted thereon, stub shafts secured to the frame and journaled in the posts, a sleeve on one of said stub shafts, sprockets on the sleeve and stub shaft respectively, a chain connection between said sleeve and the transversely disposed shaft, and pins on the chain for engaging the sprocket on the stub shaft for intermittently driving said frame.

7. In the combination with a machine of the character described, a housing having a pair of hollow posts, a transversely disposed shaft journaled in said posts, a sleeve thereon, a drum on the sleeve and a bucket connected thereto, sprockets on the shaft and sleeve respectively, a crank on the end of the shaft, and a jointed manikin connected thereto, a power plant, a chain connecting

the power plant and shaft, and means on the chain for engaging the sprocket on the sleeve, a display mechanism comprising a frame, individual display boxes pivotally mounted thereon, stub shafts secured to the frame and journaled in the posts, a sleeve on one of said stub shafts, sprockets on the sleeve and stub shaft respectively, a chain

connection between said sleeve and the transversely disposed shaft, and pins on the chain for engaging the sprocket on the stub shaft for intermittently driving said frame.

5 In testimony whereof I affix my signature.

WALTER PETTIT.
